SEWING NEEDLE

Omer J. Rainville, Attleboro, Mass.

Application June 10, 1948, Serial No. 32,162

9 Claims. (Cl. 112—224)

1

This invention relates to certain new and useful improvements in sewing needles, and in particular to sewing needles known as the self-threading type.

Among the several objects of the invention may be noted the provision of a sewing needle of the self-threading type with a resilient arm anchored at one end thereof and forming a part of the shank of the needle, the mounting thereof being so arranged as to be integral with the pointed end and presenting no obstruction to the point of the needle passing through the cloth being sewn; the provision of a sewing needle of the class described which is stronger, for its overall diameter, than previously known needles of like class; the provision of a needle of the class described in which the construction is readily adaptable to different sizes of needles in a simple and economical manner; and the provision of a needle of the class described in which a simple and yet novel means is provided to maintain the eye of the needle automatically closed during sewing operations, so that the sewing thread cannot escape therefrom. Other objects will be in part obvious and in part pointed out hereinafter.

The invention accordingly comprises the elements and combinations of elements, features of construction, and arrangements of parts which will be exemplified in the accompanying drawings, and the scope of the application of which will be indicated in the following claims.

In the accompanying drawings, in which are illustrated several views of the invention showing details of construction:

Figure 1 shows a side view of a needle blank of the present invention, after several preliminary operations have been done upon it.

Figure 2 is a side view similar to Figure 1, but after a grinding operation on the blank.

Figure 3 is a plan view of the blank of Figure 2 showing certain details of its shape.

Figure 4 is an opposite side view of the blanks of Figures 2 and 3, but with the resilient arm welded thereon, with the welded area being shown crosshatched.

Figure 5 is a plan view of the semifinished blank of Figure 4.

Figure 6 is a side view of a finished needle after the pointing of the needle has been done.

Figure 7 is a fragmentary plan view of the needle of Figure 6.

Figure 8 is a fragmentary opposite side view, in part cross sectioned and crosshatched, of the needle of Figure 6, to show certain details of

the joint between the resilient arm and the needle.

Figures 9 and 10 are cross-sectional views, taken along lines 9—9 and 10—10, respectively, of Figure 4.

Figure 11 is a perspective view of the resilient arm of Figures 4 and 5.

Similar reference characters indicate corresponding parts throughout the several drawings.

Referring now to the drawings in which I have shown the invention applied to a needle of the sewing machine type in various stages of its manufacture, at 1 is generally indicated a needle blank of the present invention and comprising a cylindrical shank 2 and an enlarged body portion or head 3, with a transverse eye 4 pierced in shank 2, and thread-clearance grooves 5 and 6 cut in the sides of shank 2. It will be noted that the center of eye 4 is located somewhat sideways of the center of shank 2 for the purpose of providing as strong a shank as possible, and likewise the thread-clearance grooves 5 and 6 are to same side of the center of the shank. An indication of the amount of side displacement may be obtained from the proportions I use in a needle having a shank diameter of .040 inch. In the latter case, with the width of the thread-clearance groove being .014 inch, the displacement sideways is .004 inch. This leaves a maximum thickness of shank on one side 7 of the groove of .009 inch, and on the other side 8 of .017 inch. The eye of the needle follows this same displacement sideways.

The full effect of this side displacement is realized upon examination of Figure 2 which shows the next step in the preparation of the needle. The thinner side 7 of the shank is ground off, as shown in Figures 2 and 3, to open a side of the eye and to leave the upstanding ribs 9 and 10. When eye 4 is so opened, the inward ends of ribs 9 and 10 constitute the front and back ends 14 and 19, respectively, of eye 4, with the original shank 2 forming one side wall, and the resilient arm 11 the other side wall of eye 4. In prior needles, with the eye and thread-clearance grooves being centrally located, when the one side is ground off, so much metal of the shank is removed as to leave the shank weaker than is necessary. By my side-displacement, less metal need be removed to open up the side of the eye, and the needle is appreciably stronger to resist bending, etc.

It will be noted from Figure 3 that thread-clearance groove 5 extends approximately the whole length of shank 2, whereas groove 6 ex-

tends only part way up said shank. The long groove 5 is for the thread coming from the thread spool on the top of the sewing machine, and groove 6 is for the thread coming from the machine shuttle.

Referring now to Figures 4 and 5, there is shown at 11 a resilient spring arm welded at one end thereof to what will later be part of the pointed end portion of the needle. It is important that the welding take place in such fashion that the weld nugget, indicated by the cross-hatching 12 of Figure 4 extend from the very end 13 of the needle to nearly the front edge 14 of eye 4. Also, the nugget in width should extend approximately the full width of wafer 11.

In so making the weld, one of the important features of the invention is realized, as will be seen by referring to Figures 7 and 8. When the end portion of the needle is tapered for pointing, as shown generally at 15, it will be observed that the taper extends through the weld nugget 12, as indicated at 16 in Figure 8, and by the cross-hatched border line 17 in Figure 7. Since the resilient arm has been welded in such fashion as to form an autogenous joint, the metal of the tapered edge 16 of the resilient arm proper forms an integral part of the metal of the shank 2, and thus no sliver can be raised or become exposed during the use of the needle.

Resilient arm 11, as shown in the perspective view of Figure 11 is preferably made of spring metal, and preferably has a cross-sectional shape forming a segment of a circle. The height of the segment may preferably be equal to the thickness of the material ground off the shank of the needle to expose ribs 9 and 10 and open up eye 4, and the radius of curvature of the convex surface of the resilient arm should preferably equal the radius of shank 2. In this way, when resilient arm 11 is welded in place, as aforesaid, it fits out and completes the shank 2 to its original roundness. It is obvious, however, that if desired, resilient arm 11 can have a rectangular cross-section, and can be any suitable thickness to give the desired spring quality. The end 18 of resilient arm 11 is rounded slightly as shown in Figure 4, in order to facilitate the introduction of a sewing thread into the passage-way between wafer 11 and rib 10.

At this point, another important feature of this invention should be described. In prior needles, some difficulty has been experienced in having the resilient arm fail to close the back end 19 of eye 4. I overcome this by providing, during the aforesaid grinding operation, that rib 9 is made slightly less in height than the rib 10. For example, in the cited example of a needle .040 inch in diameter, I remove approximately .003 inch more metal in grinding rib 9 than I do in grinding rib 10. Then, when the resilient arm 11 is welded in place it has an opportunity to bear firmly against the edge 20 of the back end 19 of eye 4 and thus close the eye securely.

A flat face 21 may be cut, if desired, on one side of head 3, to provide a bearing surface for the needle-holding screw of the sewing machine to bear against. For most common use, I prefer to place flat 21 on head 3 in such relation to resilient arm 11 that when the needle is inserted in the sewing machine for use, the arm 11 is toward the front of the machine.

To thread the needle, all that is necessary is to start the thread 22 (see Figure 6) at turned up end 18, and pull it toward eye 4 between arm 11 and rib 10 until the thread slips into place

in eye 4. Arm 11 will then spring back toward rib 10 until it rests firmly against edge 20 of eye 4, as described above, to hold the thread in the eye.

Throughout the drawings, relative thicknesses and lengths have in some instances been exaggerated in order to give clarity to the constructional details.

Since many departures may be made from the embodiments shown herein without departing from the spirit and scope of the invention, it is to be understood that all matter set forth herein or shown in the accompanying drawings is to be considered as illustrative and not in a limiting sense.

15 I claim:

1. In a sewing needle, a needle shank having a cut-away portion extending longitudinally of one side, a pair of longitudinally extending ribs rising from the cut-away portion and terminating in spaced relation to the pointed end of the needle to provide an eye, and a resilient arm overlying the cut-away portion and attached autogenously to the pointed end portion of the needle within the tapered zone thereof.

2. In a sewing needle, a needle shank having a cut-away portion extending longitudinally of one side, a pair of longitudinally extending ribs rising from the cut-away portion and terminating in spaced relation to the pointed end of the needle to provide an eye, and a resilient arm overlying the cut-away portion and attached autogenously to the pointed end portion of the needle, said ribs being spaced inwardly of the

30 25 35 sides of the shank, the place of attachment lying within the tapered zone of the pointed end portion with the tapered wall of the pointed end portion including a portion of the autogenous attachment.

3. In a sewing needle, a needle shank having a cut-away portion extending longitudinally of one side, a pair of longitudinally extending ribs rising from the cut-away portion and terminating in spaced relation to the pointed end of the

pointed end portion passing through the spot welded region.

5. In a sewing needle, a needle shank having a cut-away portion extending longitudinally of one side, a pair of longitudinally extending ribs rising from the cut-away portion and terminating in spaced relation to the pointed end of the needle to provide an eye, and a resilient arm overlying the cut-away portion and lying in close proximity to the tops of said ribs, said resilient arm, the ribs, and the uncut portion of the shank forming longitudinally extending grooves for the reception of sewing thread, the side walls of the rib adjacent the point being of equal length, one side wall of the other rib being relatively short and the other side wall extending substantially the entire length of said shank to the head of the needle, said resilient arm being attached to the needle, within the region occupied by the tapered wall of the pointed end portion thereof, by spot welding whereby an autogenous joint is formed between the end of said resilient arm and the tapered wall of the pointed end portion of the needle, the tapered wall of said pointed end portion passing through the nugget formed by said spot welding.

6. In a sewing needle, a needle shank having a cut-away portion extending longitudinally of one side, a pair of longitudinally extending ribs rising from the cut-away portion and terminating in spaced relation to the pointed end of the needle to provide an eye, and a resilient arm overlying the cut-away portion and attached to the needle by a spot welded autogenous joint lying within the tapered wall of the pointed end portion of the needle, the tapered wall of said pointed end portion passing through the region of fusion of the said arm and said needle, thereby providing an outer wall for said pointed end portion having an unbroken surface.

7. In a sewing needle, a needle shank having a cut-away portion extending longitudinally of one side, a pair of longitudinally extending ribs rising from the cut-away portion and terminating in spaced relation to the pointed end of the needle to provide an eye, a resilient arm overlying said cut-away portion and in engagement with said ribs to restore the needle partially to cylindrical formation in cross-section, said arm, ribs, and the uncut portion of the shank combining to form grooves for the reception of sewing thread, the groove on one side of said ribs being relatively short while the groove on the other side of the ribs extends substantially the entire length of said shank, said ribs being spaced mid-

way the sides of said shank, said grooves and said eye being offset of the median line of said shank to make the uncut portion of the shank relatively thicker than the resilient arm, and said arm being attached to said needle, in the region occupied by the tapered wall of the pointed end portion, by spot welding, the tapered wall of said pointed end portion passing through the region wherein the arm and needle shank have become autogenously joined together.

5 8. In a sewing needle, a needle shank having a cut-away portion extending longitudinally of one side, a pair of longitudinally extending ribs rising from the cut-away portion and terminating in spaced relation to the pointed end of the needle to provide an eye, and a resilient arm overlying the cut-away portion and attached autogenously to the pointed end portion of the needle, the rib lying adjacent to said pointed end portion being of less height than the other rib, whereby, when said arm is attached to said shank, it is caused to press against the end of said other rib which forms the eye of the needle.

15 9. In a sewing needle, a needle shank having an outer end tapered to a point; an eye adjacent the outer end; a mounting hub at the other end of the shank; one side of the shank being cut away to provide a first long rib extending along the shank from the inner end of said eye to the hub, and a second short rib extending along the shank from the outer end of said eye toward said point, and being in alignment with said first rib and of lesser height than said first rib; and a resilient arm overlying both of said 20 ribs and being attached to said shank at its outer end by spot-welding within the tapered portion of the pointed end of the needle, whereby the tapered wall of the pointed end includes a portion of the autogenous juncture thereby to 25 form a smooth unbroken surface at the place of attachment.
